UNITED STATES PATENT OFFICE.

JENNIE S. DEARBORN, OF LAKEPORT, NEW HAMPSHIRE.

DESIGN FOR A STOPPER-EXTRACTOR.

SPECIFICATION forming part of Design No. 85,097, dated September 17, 1901.

Application filed August 15, 1901. Serial No. 72,192. Term of patent 3½ years.

To all whom it may concern:

Be it known that I, JENNIE S. DEARBORN, a citizen of the United States, residing at Lakeport, in the county of Belknap and State of New Hampshire, have invented and produced a new and original Design for Stopper-Extractors; and I do declare the following to be a full, clear, and exact description of the same, reference being had to the accompanying drawing, forming a part thereof.

In the drawing is shown in perspective view a stopper-extractor embodying my invention.

As shown in the drawing, the leading or material feature of my design consists of the wire-like body A, at the upper end of which is a loop B, terminating in a bend b, which encircles the body A, an offset C toward the

lower end of the body formed by a single coil, and an offset D at the extreme lower end of the body formed by a single coil, the part a between the offsets being in line with the body.

Having described my invention, what I claim as new, and desire to secure by Letters Patent, is—

The design for a stopper-extractor, as herein shown and described.

In testimony whereof I have signed my name to this specification in the presence of two subscribing witnesses.

JENNIE S. DEARBORN.
